UNITED STATES PATENT OFFICE.

WILLIAM S. CARLSTON AND ROBERT H. HIEGER, OF KOKOMO, INDIANA, ASSIGNEES TO
BYRNE, KINGSTON & COMPANY, OF KOKOMO, INDIANA, A CORPORATION OF
INDIANA

FUEL GENERATING APPARATUS

Application filed February 9, 1927. Serial No. 166,830.

This invention relates to a fuel generating apparatus, and particularly to an apparatus which is adapted to prepare liquid fuel for effective power production in the combustion chambers of an internal combustion engine.

Specifically this invention contemplates the initial admixture of a liquid fuel with limited quantity of air, the atomization of such mixture, further heating of the atomized mixture to a relatively high temperature, then metering the highly heated mixture and mixing the same with relatively cool air to form a properly proportioned gaseous mixture for efficient combustion.

A further important object of this invention resides in the provision of improved means for idling and starting purposes.

Another important object of this invention consists in the provision of a rotary element which operates to control mixture quantity and quality, and which at the same time functions to variably increase the velocity of the main air supply.

It is finally an important object of this invention to provide an apparatus for the purpose described which may be readily calibrated, and which has a minimum of moving parts.

Other and further important objects of this invention will be apparent from the disclosures in the specification and the accompanying drawings.

The invention (in a preferred form) is shown on the drawings and hereinafter more fully described.

On the drawings:

Figure 1 is a front elevation with parts shown in dotted lines illustrating a fuel generating apparatus embodying the principles of this invention.

Figure 2 is a section on the line II—II of Figure 1 with parts shown in elevation.

Figure 3 is an enlarged fragmentary sectional view similar to Figure 2 taken on the line III—III of Figure 2.

As shown on the drawings:

The reference numeral 1 indicates the exhaust manifold of an internal combustion engine which is preferably cast integral with

an intake manifold 2, being separated therefrom by integral risers 3. The central portion of the exhaust manifold 1 is flattened as indicated at 4 and is provided with a depending flanged portion 5 on which a carburetor assembly 6 is supported by usual bolts 7.

An air introducing and mixture control mechanism is provided in a casing 8 which communicates with the intake manifold 2 through an opening 9, and which is secured to said intake manifold by suitable securing bolts. The front wall of the flattened portion 4 of the exhaust manifold is provided with a pair of substantially parallel passages 11 and 12 which extend in a substantially vertical direction and which afford chambers respectively for the preheating of air to be carburetted and for the heating of the richly carburetted air which flows therethrough during operation of the apparatus of this invention. The chamber or passage 11 terminates in a horizontal passaged boss 13 which is provided with lateral openings 14, and which has rotatably mounted thereon a cylindrical valve 15 which has an opening therein adapted to register with the opening 14, and which also has a small air inlet opening 16 therein to admit a limited amount of air into the chamber 11 for purposes of starting in a manner to be described hereinafter. The cylindrical valve 15 is operatively connected to a lateral shaft 17 which is rotatably mounted in a passage 8a in the casing 8 and which carries a choke valve 18 of usual form therein for closing the passage 8a to the flow of air. The outer end of the chamber 17 is provided with a usual crank type control lever 19 which may be connected in the usual manner for manual actuation and which is so controlled by a spring 20 as to normally hold the choke valve 18 in open position.

In order to prevent objectionable noises and also to prevent the drawing of undesirable foreign matter into passage 8a, the outer end thereof is closed by a bell shaped baffle casing 21 which permits air to flow into the passage thru openings 22 therein.

The lower end of heating chamber 11 communicates with a restricted passage 23 extending into the carbureting chamber 24 of

the carbureter assembly 6, and the lower end of the heating chamber 12 communicates with said carbureting chamber through a passage 25 which similarly is preferably smaller in cross-sectional area than the chamber 12. By virtue of this construction, air, which is preheated in the chamber 11, is drawn down into the carbureting chamber 24 where it is drawn past the carbureter nozzle 26 and richly carburetted to form an atomized fuel mixture containing a large excess of fuel. This mixture is drawn upwardly into the heating chamber 12 where it is further heated to a relatively high temperature prior to the formation of the final fuel mixture which is brought about in a manner which will now be described.

The rich highly heated mixture from the chamber 12 is discharged through a lateral connecting tube 27 and a lateral passage in the casing 8 into a second lateral chamber 28 in said casing 8. Said lateral chamber 28 in turn is provided with a plurality of outlets into the main air passage 8a in said casing 8. The first of said outlets comprises a metered idling and starting passage 29 which intersects an air passage 30 communicating with passage 8a inside the choke valve 18 in order that there may be no leakage in starting. The other passages from said passage or chamber 28, which may be termed the high speed and normal operating jets, or passages, are shown in Figure 1 at 31 and communicate with the interior of a rotary control member which will now be described.

The rotary control member which is adapted to control both the quantity and quality of the fuel mixture, as well as the velocity of the main air supply, comprises a rotatably mounted plug valve 32 which extends across the passage 8a above the choke valve 18 and which is provided with a contoured Venturi passage 33 through which the main air supply is introduced and in which said air is mixed with the highly heated rich mixture from the chamber 12. The passages, or jets, 31 previously mentioned communicate with a bearing chamber in the casing 8 in which a hollow trunnion 33a of the valve 32 is journaled. The hollow trunnion 33a is cut away as indicated at 34 so that the fuel mixture discharged from the jets 31 may be variably introduced in the interior thereof. The interior of said hollow trunnion 33a in turn communicates through a passage 34a which opens into the throat of the Venturi passage 33 in a manner best illustrated in Figure 3. The other end of the plug valve 32 is mounted on a usual trunnion which extends through a plate 35 secured to the casing 8 and secured to the end of said last mentioned trunnion is a throttle valve control crank which is designated by the reference numeral 36.

The operation of the apparatus of this invention may be briefly described as follows:

In starting the engine on which this apparatus is mounted the crank lever 19 is actuated to close the choke valve 18 which in turn brings the cylindrical valve 16 to such position that the chamber 11 only communicates with the atmosphere through the small opening 16 in said valve 15. Air drawn through this small opening enters the chamber 11 in 75 the exhaust manifold 4 and is drawn into the carbureting chamber 24 where it is richly carburetted by liquid fuel from the nozzle 26 and thence drawn through the passage 25 into the chamber 12. During this operation the plug throttle valve 32 is in closed position and the mixture for starting is drawn through the metered jet in passage 29, being mixed with a limited amount of air from the passage 30. This comprises the operation whereby a rich gaseous fuel mixture is provided for starting purposes. A somewhat similar operation is carried on when the engine is idling with the exception that the passage 30 is open to the atmosphere so 90 that sufficient additional air is admitted to secure a proper mixture for idling purposes. During idling the entering air is, of course, preheated in the chamber 11 and the mixture is further heated in the chamber 12. 95

In normal operation of the carbureter through the working and high speed ranges, the flow of air through the Venturi passage 33 and past the outer end of passage 30 is sufficient to so equalize the pressure of the 100 ends of the passages 29 and 30 as to gradually bring about a condition of equalization and render certain passages inoperative. In this normal and high speed operation the highly heated rich fuel mixture is drawn through 105 the jet or passage 31 and through the hollow trunnion 33a and passage 34a into the throat of the venturi 33 where it is thoroughly mixed while in its highly heated condition with relatively cool air entering from the passage 110 8a. The flow of the richly carburetted highly heated fuel mixture into the throat of the Venturi passage 33 is, of course, metered as the cut-out portion 34 in the trunnion 33a is more or less effective in area depending 115 upon the amount of opening of the throttle valve 32, consequently a properly proportioned highly heated gaseous fuel mixture is provided throughout the operating range. 120

By use of the apparatus of this invention satisfactory operation with low grade fuels is assured, crank case dilution is minimized, and since proper proportions are maintained through substantially the entire operating 125 range we are able to attain economical operation. Due to the fact that the passages 27 and 28 are large relative to the jet or passage 31, and relative to the idling jet, or passage, 29 a reserve of richly carburetted fuel 130

mixture is maintained at all times for acceleration and idling.

Due to the fact that a large proportion of the air enters the mixture at substantially atmospheric temperature the beneficial results of this apparatus are attained without loss of volumetric efficiency.

The apparatus of this invention may be easily calibrated, economically manufactured, and contains a minimum of moving parts which are likely to get out of order.

We are aware that numerous details of construction may be varied through a wide range without departing from the principles of this invention and we therefore do not purpose limiting the patent granted hereon otherwise than necessitated by the prior art.

We claim as our invention:

1. In a device of the kind described, an air preheating chamber, means communicating therewith whereby the air heated in said chamber may be richly carburetted with liquid fuel, a second chamber in which said carburetted air is heated to a relatively high temperature, means for regulating the flow of such high temperature carburetted air from said chamber, means for mixing such highly carburetted heated air with a relatively large quantity of relatively cool air as it flows from said metering means and a single means for controlling said last mentioned air admitting means and said regulating means.

2. In a device of the kind described, an air preheating chamber, means communicating therewith whereby the air heated in said chamber may be richly carburetted with liquid fuel, a second chamber in which said carburetted air is heated to a relatively high temperature, means for regulating the flow of such high temperature carburetted air from said chamber, means for mixing such highly carburetted heated air with a relatively large quantity of relatively cool air as it flows from said metering means and a rotary means for controlling said last mentioned air admitting means and said regulating means.

3. The combination with an internal combustion engine and the exhaust and intake manifolds thereof, of a pair of heating chambers formed in a wall of the exhaust manifold, a carbureting chamber separately connected to said heating chambers, a controllable air inlet to one chamber, a controllable mixture outlet from the other chamber, and means for introducing relatively large quantities of relatively cool air into the mixture flowing from said mixture outlet.

4. The combination with an internal combustion engine and the exhaust and intake manifolds thereof, of a pair of substantially parallel heating chambers formed in a wall of the exhaust manifold, a carbureting chamber separately connected to said heating chambers, a controllable air inlet to one chamber, a controllable mixture outlet from the

other chamber, and means for introducing relatively large quantities of relatively cool air into the mixture flowing from said mixture outlet.

5. The combination with an internal combustion engine and the exhaust and intake manifolds thereof, of a pair of heating chambers formed in a wall of the exhaust manifold, a carbureting chamber separately connected to said heating chambers, a controllable air inlet to one chamber, a controllable mixture outlet from the other chamber, means for introducing relatively large quantities of relatively cool air into the mixture flowing from said mixture outlet, and means of limited cross-sectional area communicating with said second mentioned chamber and with the intake manifold through which fuel mixture is introduced for starting and idling the engine, said last mentioned means also communicating with the air introducing means.

6. The combination with an internal combustion engine and the exhaust and intake manifolds thereof, of a pair of heating chambers formed in a wall of the exhaust manifold, a carbureting chamber separately connected to said heating chambers, a controllable air inlet to one chamber, a controllable mixture outlet from the other chamber, means for introducing relatively large quantities of relatively cool air into the mixture flowing from said mixture outlet, the connections between the carbureting chamber and said heating chambers being of smaller cross-sectional area than the cross-sectional area of the heating chambers.

In testimony whereof we have hereunto subscribed our names at Kokomo, Howard County, Indiana.
